UNITED STATES PATENT OFFICE.

THOMAS GORDON, OF PERTH, WESTERN AUSTRALIA, AUSTRALIA.

PUMP PLUNGER.

Application filed November 29, 1921. Serial No. 518,709.

To all whom it may concern:

Be it known that I, THOMAS GORDON, a subject of the King of Great Britain, residing at Excelsior House, Murray Street, 5 Perth, Western Australia, Commonwealth of Australia, have invented certain new and useful Improvements in Pump Plungers, of which the following is a specification.

My invention relates to that type of pump 10 plungers in which cup leathers are employed and the object thereof is to produce a more efficient plunger for which the air is fed to the compression side of the plunger in an abundant manner and preparatory to 15 the compression stroke being made.

The chief structural feature of the invention resides in forming the metal plunger head with peripheral marginal inlets or passages which allow the feed air to flow 20 freely to the compression side of the plunger during the idle or return stroke—said feed air flows through said passages and circumferentially between the cup leather and the wall of the cylinder or barrel.

25 A further structural feature in combination resides in the metal plunger head having on its compression side or face a peripheral or marginal recess or rabbet formation thus thereat providing a gap or cavity to 30 allow the cup leather to freely and outwardly expand or bulge and prevent the escape or return of any air to the feed side of the plunger during its compression stroke. The resultant air pressure on the said compression side automatically causes said cup leather to expand and to be maintained in such 35 expanded position during the said compression stroke. My invention prevents (as hitherto the practice) the plunger during its 40 compression stroke from moving a certain distance in its cylinder practically idle and before it becomes fully effective as a pumping agent and by my invention loss of time and high pressure air is avoided. In order 45 that the invention may be clearly understood reference will be made to the attached drawings wherein—

Fig. —1— is a view partly in elevation and partly in section showing a pump plunger made in accord with this invention and in said view the cup leather is shown in its normal or unexpanded position and the flow of the feed air is denoted by the full arrows. Fig. —2— is a plan view.

50 Referring to said drawings the metal plunger head as *a* is held on the reduced end

portion *b* of the rod *c* and secured by the loose metal washer *d* and nut *e*. In the peripheral margin of said plunger head are formed a number of inlets or openings *f* 50 which (when the plunger is at its return or idle stroke) act as inlets and passages for the air from the feed side *x* of the plunger for the therethrough passage of feed air to the opposite or compression side *y* of said 55 plunger. The plunger head *a* is made with a peripheral or marginal recess or rabbet *m* which thereby and thereat provides a cavity or gap to permit of the flexible expansion of the cup leather *j*. This cup leather as clearly 60 seen in Fig. —1— is held in position between the loose metal washer *d* and the reduced or rabbeted portion *m* of the plunger head—said washer in practice is smaller in diameter than the rabbet *m*. In the working of 65 the invention assume that the plunger head *a* and cup leather is at the idle or return stroke and moving in the direction of the broken arrow shown in Fig. —1— the feed 70 air as denoted by the full arrows consequent- 75 ly rushes freely from the feed side *x* of the plunger and through the peripheral openings *f* of the plunger head *a* and circumferentially between the cup leather *j* and the wall *n* of the cylinder—said air then 80 passes into the compression side *y* for the subsequent compression stroke and immediately upon the start of such stroke the cup 85 leather *j* by reason of the resultant air pressure will automatically and outwardly 90 expand and make close contact against the wall *n* of the cylinder and which expansion is facilitated and made more positive by the relief cavity formed by the rabbet *m* of 95 the plunger head *a* and said cup leather by 100 said expansion provide a tight close seal against the escape or return of air from said compression side *y* during the compression stroke of the plunger. The rush of air through the openings *f* has the further tendency to reduce the normal size of the cup leather *j* and thus form an effective free air way during the return or idle stroke of the 105 plunger aforesaid.

It will therefore be clearly seen that this 110 invention produces an instant compression at the start of the compression stroke as the compression side as *y* is initially and completely filled with air prior to the start of such stroke and hence the plunger is rendered highly effective for the full length of such stroke as a pumping agent.

The present application is a continuation in part of my prior application, Serial No. 377,846, filed April 30, 1920.

What I claim as my invention and desire 5 to secure by Letters Patent is:—

1. In combination with a pump cylinder, a pump plunger head equal in diameter to the bore of the cylinder, a cup leather secured to the compression side of the pump head, said head being formed with marginal openings on its periphery and with a peripheral marginal rabbet or recess to thereby and thereat provide a relief cavity for the outward expansion of the cup leather 10 and to cause same to make close contact against the wall of the plunger cylinder during the compression stroke of said plunger as herein described and shown in the attached drawings.
2. In combination with a pump cylinder, a pump plunger head equal in diameter to the bore of the cylinder, a cup leather on the compression side of the head, said head being formed with marginal openings to 15 provide air inlet passages for the free feeding of air to the compression side of the plunger during its idle or return stroke—said plunger being also formed with a marginal rabbet to provide a relief cavity for 20 the outward expansion of the cup leather during the compression stroke of the plunger said plunger head and cup leather in operative combination with each other and with a pump barrel or cylinder as herein 25 set forth and described and shown in the attached drawings.

3. A pump plunger comprising a head having marginal openings and having a circumferential depression on its compression

side, a cup leather on the compression side 40 of the head and a washer of smaller diameter than said head, positioned against said cup leather, and a nut for securing said cup leather and washer in place.

4. In combination with a pump cylinder, 45 a plunger comprising a head equal in diameter to the bore of the cylinder, said head having a circumferential depression on the compression side of the head and peripheral passageways communicating therewith, a 50 cup leather secured to the compression side of the head and extending over said depression.

5. A pump comprising a barrel, a plunger rod reciprocable within said barrel, a 55 piston head secured to said plunger rod having a back portion of slightly smaller diameter than said barrel to form an air leak therebetween, and a front face of smaller diameter than said back portion, forming 60 with said barrel a circumferential recess, a washer of smaller diameter than the front face of said piston, a cup leather clampably held between said washer and front face, having a flexible portion bending away from 65 said piston head at the edge of said washer on the suction stroke, and being successively pressed into contact with said front face and into said recess, with increase of pressure upon the compression stroke.

In testimony whereof I have hereunto set 70 my hand in presence of two subscribing witnesses.

THOMAS GORDON.
